(57) **CLAIM**

The ornamental design for a nasal cannula, as shown and
described.

DESCRIPTION

FIG. 1 is a top, front and right side perspective view of a
nasal cannula embodying our new design.

FIG. 2 is a top, rear and right side perspective view thereof.

FIG. 3 is a top view thereof.

FIG. 4 is a bottom view thereof.

FIG. 5 is a right side view thereof.

FIG. 6 is a left side view thereof.

FIG. 7 is a front view thereof; and,

FIG. 8 is a rear view thereof.

Dash-dash broken lines are used to illustrate portions of the
nasal cannula which form no part of the claimed design.
Dash-dot broken lines define the bounds of the claimed
design and form no part thereof.
